(Cl. D34—15)

To all whom it may concern:

Be it known that we, Louis A. Goodman and Norman S. Levy, citizens of the United States, residing at Chicago, in the County of Cook and State of Illinois, have invented a new, original, and ornamental Design for a COMBINATION TOY WHEELBARROW AND ROCKER, of which the following is a specification, reference being had to the accompanying drawing, forming part thereof, in which—

Fig. 1 is a side elevational view of a combina-

tion toy wheelbarrow and rocker showing our new design;

Fig. 2 is a top plan view;

Fig. 3 is a bottom plan view; and

Fig. 4 is a rear end elevational view thereof.

We claim:

The ornamental design for a combination toy wheelbarrow and rocker, as shown.
